UNITED STATES PATENT OFFICE

118,612

DESIGN FOR A MINE SHUTTLE CAR

George Baechli, Franklin, Pa., assignor to Joy
Manufacturing Company, Franklin, Pa., a cor-
poration of Pennsylvania

Application November 16, 1939, Serial No. 88,330

Term of patent 14 years

To all whom it may concern:

Be it known that I, George Baechli, a citizen
of the United States and residing at Franklin,
in the county of Vanango and State of Pennsyl-
vania, have invented a new, original, and orna-
mental Design for a Mine Shuttle Car, of which
the following is a specification, reference being
had to the accompanying drawings, forming a
part thereof, wherein:

Fig. 1 is a front perspective view of a mine
shuttle car embodying my invention;

Fig. 2 is a perspective view of the mine shuttle
car showing the front and one side of the car;

Fig. 3 is a perspective view showing the rear
and the other side of the mine shuttle car; and

Fig. 4 is a perspective view of the side partly
shown in Fig. 2.

I claim:

The ornamental design for a mine shuttle car,
as shown.

GEORGE BAECHLI.
